UNITED STATES PATENT OFFICE.

DAMIAN L. REYNOLDS, OF SAN FRANCISCO, CALIFORNIA, ASSIGNOR OF ONE-HALF TO
LUTHER L. YATES, OF SAN FRANCISCO, CALIFORNIA.

REFRIGERATOR CAR.

Application filed January 8, 1923. Serial No. 611,481.

To all whom it may concern:

Be it known that I, DAMIAN L. REYNOLDS, a citizen of the United States, and a resident of the city and county of San Francisco, 5 in the State of California, have invented a new and useful Refrigerator Car, of which the following is a specification.

This invention relates to vehicles for the transportation of cargo, such as freight cars, 10 and more particularly to the construction of refrigerator cars.

It is one of the objects of my invention to provide a refrigerator car that is well adapted to withstand the rough handling 15 incident to railroad operation, and that is constructed in such a way that those parts most likely to require replacement or repair may readily be removed for that purpose. It is another object of my invention to provide 20 an improved form of bulkhead construction between the ice compartment and the cargo compartment that is more desirable in service than prior forms.

Although refrigerator cars are especially 25 designed for the shipment of perishable cargo, such as fruits, they are very often used for other classes of freight. This condition is a common one for example where, as on the Pacific coast, the amount of perishable 30 outgoing freight far exceeds the amount of such freight that is incoming. Instead of returning the surplus refrigerator cars empty to the Pacific coast, it is common to utilize the cargo space for durable 35 freight. When such cars are used for this service, it has been comparatively easy for looters without detection to enter the car through the ice loading hatchway, and to gain access from the ice compartment to 40 the cargo compartment by either battering away the bulkhead between the compartments, or else by removing the grate bars upon which the cakes of ice are adapted to rest, and utilize the air ducts thereunder 45 for extracting some of the cargo. It is still another object of my invention to obviate such occurrences. This I accomplish by constructing the ice grate and the bulkhead so as to conceal and protect from destruction 50 the various fastening devices employed in the construction of these elements, and also by choosing materials of such characteristics that it is difficult to bend, cut, break or loosen the component parts of the 55 bulkhead or of the ice grate.

My invention possesses other advantageous features, some of which, with the foregoing, will be set forth at length in the following description, where I shall outline in full those forms of the invention 60 which I have selected for illustration in the drawings accompanying and forming part of the present specification. Although I have shown in the drawings but a few embodiments of my invention, it is to be 65 understood that I do not desire to be limited thereto, since the invention as expressed in the claims may be embodied in other forms also.

Referring to the drawings: 70
Figure 1 is a cross sectional view taken along plane 1—1 of Fig. 2 of a car embodying my invention;

Fig. 2 is a horizontal sectional view, taken along plane 2—2 of Fig. 1, of the ice compartment and bulkhead shown in Fig. 1;

Fig. 3 is a vertical sectional view, taken along plane 3—3 of Fig. 1 of the ice compartment and bulkhead;

Fig. 4 is a detail perspective view of 80 one of the elements of the metal screening used in the bulkhead construction;

Fig. 5 is an enlarged vertical sectional view of the ice grates and their supports, showing the manner in which they are 85 locked in place;

Fig. 6 is an enlarged detail view, partly in section, of the locking arrangement for the grate;

Fig. 7 is a sectional view, mainly diagrammatic illustrating the manner in which the grates may be removed for cleaning or repairs after they are unlocked; and

Figs. 8 and 9 are enlarged detail views of modified forms of construction for the 95 bulkhead.

In the present instance my invention is shown as applied to a refrigerator car having the usual construction for its exterior walls, but it is of course possible to utilize 100 the invention in connection with other types of cargo carrying vehicles. The exterior wall construction shown forms no part of my present invention, and it is therefore unnecessary to set forth a detailed description thereof. Referring to Figs. 1, 2, and 3, the car floor 11, the sides 12, and the top 13 are shown as made up of several layers 105 of materials adapted to provide a heat insulating construction. In the sloping top 110

13 there are provided one or more hatches 14 that are removable for permitting ice to be placed into the ice compartment 15, located at the end of the car. It is through 5 these hatchways that looters or other unauthorized persons may readily secure entrance into the car without material risk of detection, either while the car is at rest in a yard, or moving with its cargo in a train. 10 A bulkhead or wall 16 separates the ice compartment 15 from the cargo compartment 17. In the present instance I utilize a series of vertically extending metal sections 18, shown as formed integral along 15 their lateral sides with the channel shaped sides or flanges 19. The sections 18 abut along these sides 19, as shown most clearly in Figs. 1 and 2, and in fact they may be fastened together as by welding, riveting 20 or bolting. Furthermore it may under certain circumstances be advisable to utilize standard structural channel shapes or even wood posts for these sides 19, in which case the members 18 will be simply flat pieces of 25 sheet metal attached to the channel flanges or to the sides of the post. These latter modifications are illustrated in Figs. 8 and 9, respectively. In Fig. 8, the channels 56 are placed back to back to form a columnar 30 support for the members 18; and in Fig. 9, the wood post 57 serves this purpose.

On the cargo side of these members 18, there may be provided a wall construction 20, formed of appropriate layers of such 35 material as wood, paper and hairfelt, and fastened to the free edges of the side members 19. This wall 20 does not extend entirely from top to bottom of the car; instead there is a substantial space between 40 the top of the wall 20 and the roof of the car, as well as between the bottom of wall 20 and the floor of the car. In this way it is possible, by providing appropriate openings at the top and bottom of members 18, 45 to secure a circulation of air between the ice compartment 15 and the cargo compartment 17. As shown most clearly in Fig. 4, a series of perforations 21 near the top of these members and an opening 22 near the bottom thereof serve this purpose. Air 50 from the cargo compartment 17 may then enter the ice compartment 15 through apertures 21, travel downwardly through the ice compartment, and out through openings 55 22 back into the cargo compartment 17.

One of the important features of the construction of the bulkhead 16 is the manner in which it is fastened to the interior of the car, whereby the fastening means are inaccessible from the ice compartment 15. Thus at the top, the members 18 have a horizontal flange 23, extending backwardly toward the cargo compartment 17, which is fastened, as by lag screws 24, to the roof timber 25. At the bottom, a series of shoes

26 is provided, fastened to the sill 27 at the edge of the ice compartment 15, and each of the shoes has an upstanding ear 28 that is adapted to enter into the channeled sides 19 and to be riveted thereto, as shown most clearly in Fig. 3. It is impossible to gain access to the shoes 26 from the ice compartment 15, because the ice grate 29 which is locked in position, intervenes between this compartment and the shoes. Similarly, the lag screws 24 at the top of the bulkhead 16 cannot be reached except from the cargo compartment.

The abutting sides 19 of adjacent metal sections 18 provide substantially a series of rigid posts or columns between which the sections 18 extend, and at the bottom of which the supporting shoes 26 are attached. It is to be noted that between these posts or columns, the sections 18 possess considerable resiliency, and it is a very difficult matter by ordinary pounding for example with a hammer or crowbar to loosen these sections or to bend or break them. By proper choice of either soft metal or of specially treated metal, it is possible to increase its resistance to such usage. Furthermore I prefer to space the apertures 21 at the top of the sections 18 relatively far apart so that a substantial amount of metal between apertures may be left.

The ice in compartment 15 rests upon the grate 29, underneath which is disposed a rust-proof drip pan 30. Drains 31 with guards 32 may be provided to carry off the water that collects in the pan 30 from the ice as it melts. The grate 29 is formed of a series of parallel bars 33, shown in the present instance as formed of T-bars, with the horizontal leg lowermost and appropriately fastened, as by welding, to the supporting angles 34, 35. The entire grate assembly is adapted to be held between a pair of guide supports 36 and 37, in the present instance shown as channel irons between the flanges of which the ends of bars 33 are disposed. These grate bars 33 are for this purpose narrowed down at the ends, as shown at 38, so that these ends may readily enter between the flanges of the channels 36 and 37, while at the same time the ice is permitted to rest upon the high portion of the bars and to clear by an appreciable amount the tops of the supports 36 and 37. The channel 36 is fastened to a series of rests 39. These rests each have a portion 40 resting against the back of the channel 36, another portion 41 upon which the bottom flange is disposed, and a vertical portion 42. This latter portion serves, in combination with the other extremity of rest 39, for the attachment of these rests to the inside of the car. As shown most clearly in Fig. 2, the channels 36 and 37 extend substantially entirely across the car. In order to close up

the ends of the channels in a secure manner, angle irons 58 are utilized at these points.

For purposes of cleaning or repairs, it is required that the grate 29 be readily removable from its supports 36 and 37. It is for facilitating this removal that the grate 29 is made up in a plurality of sections, so that it may, section by section, be slipped in between the flanges of the channels 36 and 37, at a place, such as 43, where the top flange is cut away to permit this insertion of the grates. In the present instance there are four grate sections, but of course as many sections could be provided as may be necessary. These four sections, as shown most clearly in Fig. 1, may be enumerated as follows: The first section at the extreme right of this figure includes those bars 33 that are attached to the supports 34; the second section includes those bars that are attached to supports 35. The third and fourth sections are the symmetrical equivalents of the second and first respectively. The open portion 43 of the supports 36 and 37 is located so that a comparatively slight sliding movement of one of the sections within supports 36, 37 is sufficient to position the section properly for its removal. Thus in this instance that section supported on bars 35 at the right of Fig. 1 may be slid slightly to the right and then lifted out through the space 43, as indicated most clearly in Fig. 7. In order to facilitate the removal of all of the sections, even those remote from the opening 43, the sections may be connected to each other to permit relative movement between them. For this purpose supports 34 and 35 are hinged together, as by the aid of the pivot pin 44. This pin is located directly underneath the center of one of the bars 33, so that it may the better be out of reach of an unauthorized person in the ice compartment 15. By withdrawing the second section of the grate 29, the first section may also readily be passed through the opening 43. After this is accomplished, the third and fourth sections may in a similar manner be removed. The reverse operation of inserting the grate is evident from the description of its removal.

In order to prevent the unauthorized removal of the grate bars, I prefer to provide a lock for them, whereby it is impossible to slide the sections within the channel guides 36 and 37. In this way, the openings 22 in the bulkhead 18 are out of reach and the car cannot be readily pilfered. The locking arrangement is shown most clearly in Figs. 3, 5, 6 and 7 and includes a pair of locking bars 45, shown in the present instance as a bolt of any usual type. These bars 45 are arranged to engage slots 46 located at the bottom of the supports 35 for the two central grate sections. The bars 45 may however be dropped so as to clear these slots and

permit movement of the grate sections. For this purpose a member 47 is fastened, as by welding, to the bottom flange of support 36, and has a pair of slots 50 to accommodate both rods 45. A rib or bead 48 on member 47 is adapted to engage the heads 49 of the bolts 45 and prevent their removal from the slot 50. The other support 37 carries an apertured member 51 through which bolt 45 projects. Nuts 52 serve to hold the rod or bolt 45 in place, and the extremity of the rod is upset as shown at 53 to prevent the nuts from being removed. By loosening nuts 52 sufficiently, the rod 45 may readily be pushed to the right far enough so that its head 49 clears the bead 48, and the rod is free to drop below the supports 34. Sufficient clearance is permitted for these bars in the member 51 so as to permit complete disengagement of the rod 45 from the slots 46 in the supports 34. The nuts 52 may be manipulated only from the cargo side of bulkhead 16. A looter in the ice compartment 15 is thus effectually prevented from lifting out the grate bars.

In order to prevent the ice from coming in contact with the sides of the car, I prefer to cover the sides of the ice compartment with wire screening 54 except the bulkhead side. This screening may be attached in any appropriate manner, as for example to the channel 36 and the angle irons 42. A relatively narrow strip 55 of the screening may also be placed back of the bulkhead openings 21, in the cargo compartment 17.

I claim:

1. In a cargo vehicle having a pair of compartments, a bulkhead between the compartments, comprising a plurality of flat metallic sections, channel shaped sides attached to the backs of the sections, the sides of adjacent sections being in abutting relation and forming a column, and means for fastening the side members together.
2. In a cargo vehicle having a pair of compartments, a bulkhead between the compartments, comprising a plurality of flat metallic sections having abutting flanges at their adjacent edges, said flanges extending only on one side of the sections, whereby one of the flat surfaces formed by the plurality of sections remains uninterrupted.
3. In a vehicle having an ice compartment and a cargo compartment, a bulkhead between the two compartments, comprising a plurality of abutting metallic sections, abutting sides for the sections extending in one direction only, said sides forming posts, and supports for the posts, said supports each being attached to the interior of the vehicle and each having an extended projection engaging with the extremity of its corresponding post.
4. In an ice compartment for a cargo vehicle, bars forming an ice grate and ar-

90

115

120

125

130

- 4 ranged to support ice located in the space above them, and means comprising stationary and movable parts for locking the bars in place, all of the movable parts being wholly external of said space. 5
5. In an ice compartment for a cargo vehicle, bars forming an ice grate, supporting bars below the grate to which supporting bars the grate bars are attached, guides 10 for supporting the grate within the compartment, said grate being slidable in the guides for removing it, and means for preventing the grate from sliding. 6
6. In an ice compartment for a cargo vehicle, a series of bars forming an ice grate, 15 a plurality of mechanically connected but relatively movable supports for the bars, forming therewith grate sections, and a guide for the sections, said guide having a pair of flanges forming a channel for 20 accommodating the ends of the bars, one of the flanges being cut away for a short space in order to permit the removal of the grate sections. 25
7. In an ice compartment for a cargo vehicle, a series of bars forming an ice grate, 30 a plurality of mechanically connected but relatively movable supports for the bars, a guide having a pair of flanges forming a channel for 35 accommodating the ends of the bars, one of said flanges being so formed that the sections may be inserted and removed from the guide, and means for locking the sections against movement relatively 40 to the guide. 45
8. In an ice compartment for a cargo vehicle, a plurality of grate sections connected pivotally, a channel guide member extending substantially entirely around the compartment for the grate sections, one of the flanges of the channel being interrupted so as to permit withdrawal of the grate sections, and locking bars engaging one of the sections for preventing them from being 50 moved. 55
9. In an ice compartment for a cargo vehicle, a plurality of grate sections hingedly connected together, a guide having flanges between which the edges of the grate sections are disposed, the top flange being cut away for a short distance to permit withdrawal of the grate, and a locking bar below the grate engaging one of the sections for preventing its removal. 60
10. In an ice compartment for a cargo vehicle, a plurality of grate sections near the bottom of the compartment and arranged to support ice located in the space above them, and means for locking the sections against 65 removal, comprising a locking bar engaging the grate and accessible only from outside said space, and releasing means on said bar. 70
11. A cargo vehicle having an ice compartment, a cargo compartment, a bulkhead 75 between the compartments, and a removable
- ice grate near the bottom of the ice compartment, said grate being arranged to support ice in the space above it, characterized by the fact that means are provided for fastening in the bulkhead that is located entirely exterior to said space, and that locking means for the grate is provided, having movable and stationary parts, all of the movable parts being also located exterior to said space. 75
12. In an ice compartment for a cargo vehicle, bars forming an ice grate, grooved guides for slidably supporting the bars in the compartment, and means for preventing the bars from sliding. 80
13. In an ice compartment for a cargo vehicle, a series of bars forming an ice grate, and a guide for the bars, said guide having a pair of flanges forming a channel for 85 accommodating the ends of the bars, one of the flanges being cut away for a short distance in order to permit the removal of the bars. 90
14. In an ice compartment for a cargo vehicle, a series of bars forming an ice grate, a guide for the bars, said guide having a pair of flanges forming a channel for 95 accommodating the ends of the bars, one of the flanges being cut away for a short distance in order to permit the removal of the bars, and means cooperating with the grate for locking the bars against movement relatively to the guide. 100
15. In a refrigerator car having an ice compartment and a cargo compartment, a bulkhead between said compartments comprising a plurality of vertically extending sections placed with their vertical lateral edges substantially abutting, each of said sections comprising a sheet metal wall having flanged lateral edges for reinforcing said wall, means for connecting the lateral flanges of adjoining sections, a horizontally extending flange at the upper end of each section, means for securing said horizontally extending flange at the upper part of the car, a sill member secured to the floor of the car, and means for fastening the lower ends of said lateral flanges to said sill members. 105 110
16. In a refrigerator car having an ice compartment and a cargo compartment, a grate supported in the bottom of said ice compartment, horizontal guides for said grate, said grate being shiftable between 115 two positions on said guides, and means for preventing the removal of said grate when in one of said positions. 120
17. In a refrigerator car having an ice compartment and a cargo compartment, a grate supported adjacent the bottom of said ice compartment, horizontal guides for said grate, said grate being shiftable between two 125 positions on said guides, means for preventing removal of said grate when in one of 130

said positions, and lock means releasable only from said cargo compartment for holding said grate in said last-named position.

18. In a refrigerator car having an ice compartment, a pair of grate sections supported adjacent the bottom of said ice compartment, said grate sections being pivotally connected, guide means for said grate sections permitting shifting movement of the

latter, said pivoted grate sections being removable from said guide means when shifted to one position relative to said guide means, and means for locking said grate sections against removal when shifted to another position relative to said guide means. 15

In testimony whereof, I have hereunto set my hand.

DAMIAN L. REYNOLDS.
